(57) **CLAIM**

We claim the ornamental design for shielding for a bale press, as shown and described.

DESCRIPTION

FIG. 1 is a front perspective view of shielding for a bale press showing our new design;

FIG. 2 is a left side view thereof;

FIG. 3 is a right side view thereof;

FIG. 4 is a top view thereof;

FIG. 5 is a rear view thereof; and,

FIG. 6 is a rear perspective thereof.

Only the shapes and portions bounded by solid lines form the claimed design. The bottom view is not visible during normal use of the machine and does not form part of the claimed design and therefore is not shown or disclosed. The elements depicted in dashed lines are shown for illustrative purpose of environment and form no part of the ornamental design.
